THREE DIMENSIONAL APPLIED WALL-HANGING OR SIMILAR ARTICLE

Norma I. Hovdal, 3644 19th St., San Francisco, Calif.

Filed July 24, 1963, Ser. No. 75,951

Term of patent 14 years

(Cl. D29—23)

Fig 2

The back of my new design is substantially plain and unornamented.

I claim:

The ornamental design for a three dimensional applied wall-hanging or similar article, substantially as shown and described.
